UNITED STATES PATENT OFFICE

137,336

DESIGN FOR A SERVICE PIN

Homer W. Brown, Norfolk, Va.

Application July 2, 1943, Serial No. 110,584

Term of patent 7 years

To all whom it may concern:

Be it known that I, Homer W. Brown, a citizen of the United States, residing at Norfolk, in the county of Norfolk and State of Virginia, have invented a new, original, and ornamental Design for Service Pin, of which the following is a specification, reference being had to the accompanying drawing, forming part thereof.

Fig. 1 is a front elevation of a service pin, showing my new design.

Fig. 2 is a top edge view of the same.

I claim:

The ornamental design for a service pin, as shown.

HOMER W. BROWN.
